THERMAL TIMER FOR TOASTERS

John R. Gomersall, Elgin, Ill., assignor to McGraw
Electric Company, Elgin, Ill., a corporation of
Delaware

Application April 10, 1940, Serial No. 328,829

8 Claims. (Cl. 161—16)

My invention relates to automatic electric toasters and more particularly to thermal timers for such toasters.

An object of my invention is to provide a novel form of thermal timer operating on the heat-up cool-off cycle for controlling the duration of a toasting operation and for terminating the toasting operation.

Another object of my invention is to provide a relatively simple structure for such a thermal timer which comprises a relatively few parts and which can be easily and quickly manufactured and assembled in mass production.

Other objects of my invention will either be apparent from a description of one form of timer embodying my invention or will be pointed out in the course of such description and will be set forth in the appended claims.

In the drawings:

Figure 1 is a vertical lateral sectional view taken on the line 1—1 of Fig. 3, the parts being shown in non-toasting position,

Fig. 2 is a fragmentary vertical sectional view taken on the line 2—2 of Fig. 1,

Fig. 3 is a sectional side elevational view taken on the line 3—3 of Fig. 1 the parts being shown in non-toasting position,

Fig. 4 is a fragmentary bottom view of the parts shown in Fig. 3 with the bottom cover removed and showing the normal position of certain parts of the timer structure,

Fig. 5 is a fragmentary front view of the toaster showing more particularly the manually adjustable knob for regulating the toasting time,

Fig. 6 is what may be called an exploded view of certain parts of the timer and latch structure, parts being shown as positioned in the same plane although actually they are positioned in planes extending at right angles to each other,

Fig. 7 is a view similar to Fig. 6, but showing parts of the timer structure in different positions, and,

Fig. 8 is a fragmentary view similar to Fig. 6, showing parts of the timer structure in other positions.

Reference may here be made to my copending application Ser. No. 328,828 filed as of even date herewith and assigned to the same assignee as is the present application in which parts of the toaster structure itself are disclosed, described and claimed, and in the following description of the toaster structure reference will be made to only the major portions thereof and reference may be had to my above identified copending application for details of the structure itself. This

application is to cover more particularly the thermal timer means operating on a heat-up cool-off cycle for each toasting operation.

An automatic electric toaster designated generally by the numeral 21 includes a bottom skeleton frame 23 which may be made of a suitable moulded composition and which may have associated therewith adjacent its upper edge, a bottom plate 25 which, as shown, may be of inverted open-box shape which may be secured against the upper face of the skeleton frame 23 in any suitable manner. The toaster includes also a casing 27 which includes two side walls, a front and a rear wall, and a cover, which cover is provided with a plurality of longitudinally-extending slots in a manner well known in the art to permit of insertion of slices of bread to be toasted in the toaster and of removing the toasted slices of bread therefrom when they have been properly toasted.

I provide also a plurality of pairs of vertically-extending planar heating elements each including one or more thin sheets 29 of electric insulating material such as mica, having wound thereon a heating resistor conductor 31, all in a manner well known in the art. I provide further a rear intermediate wall 33 and a front intermediate wall 35 which may cooperate with the pairs of spaced vertical electric heating elements to provide one or more toasting chambers within the outer casing 27. I have elected to show my invention as applied to a two-slice toaster but do not desire to be limited thereto as my new and improved thermal timer may be associated with a toaster structure designed and constructed for simultaneously toasting one or any desired number of slices of bread.

I provide a number of bread carriers 37 equal in number to the number of toasting chambers, 40 which bread carriers are movable vertically relatively to the above described toast heating elements, the bread carriers being movable from an upper non-toasting position, all in a manner well known in the art.

45 I provide a single vertical standard 39 having its lower end properly secured as by interfitting with the bottom plate 25 and by having its upper end held by a bracket 41 secured to the front intermediate wall 35. A carriage plate 43 is vertically movable on the standard 39 and has lateral rearwardly-extending flanges 45 at each side thereof to which the front end portions of the bread carriers 37 are connected so that downward movement of the carriage 43 will result in downward movement of the bread carriers. I provide

an auxiliary plate 47 on the carriage 43, which auxiliary member has limited vertical movement on pins 49 as set forth in my copending application referred to above. The auxiliary member 47 is provided with a forwardly extending projection 51 which may project outwardly through the front wall of the casing 27 and have mounted thereon a manually actuatable knob 53. Downward pressure on knob 53 will cause downward movement of the carriage 43 and of the bread carriers 10 connected therewith against the tension of a biasing spring 55 which has its lower end connected to a suitable part of the carriage 43 and which may have its upper end connected to bracket 41 thereby normally yieldingly biasing the bread carriers into their upper non-toasting position. In order to maintain the carriage and the bread carriers in their proper operative position relatively to the toasting chamber, I may provide a pair of rollers 57 connected to each of the respective flanges 45, these rollers engaging the front surface of the front intermediate wall 35 thereby holding the bread carriers as well as the carriage plate in their proper operative positions. The front end portions of the bread carriers 37 move in slots 59 in the front intermediate wall 35.

Since the biasing spring 55 causes quick upward movement of the carriers at the end of a toasting operation, I may provide an air cylinder 61 having its upper end secured to and held by the bracket 41 and a piston movable therein and mounted on a piston rod 63 which has a lost motion connection with the carriage plate 43 so that when the spring 55 becomes effective to quickly move the bread carriers and the carriage upwardly, the air cylinder 61 will act as a shock absorber in a well known manner.

I provide a latch arm 65 which is pivotally mounted intermediate its ends, on the carriage plate 43 and which has a lower catch portion 67 adapted to engage with a detent 69 of substantially L-shape pivotally mounted on a bracket 70 secured to the under side of plate 25. The detent 69 has pivotally mounted thereon a latch-holding projection 71, the design and construction of members 69 and 71 being shown substantially in Fig. 1 of the drawings and it will be noted that the member 71 is positioned slightly angularly relatively to a horizontal line or plane and that portion 67 of member 65 also extends slightly angularly relatively to a horizontal plane so that easy and quick separation of the two parts may be effected when the timer to be hereinafter described is effective to cause such release and thereby the termination of a toasting operation.

The carriage 43 may have mounted thereon and secured thereto, a resilient support 73 having mounted thereon a contact bridging member 75 which is suitably insulated from the spring member 73 and which is adapted to engage with a pair of contact members 77 insulatedly mounted on and supported against the upper surface of member 25.

The thermal timer more particularly comprising my invention consists of a bimetal bar 79 and a rigid bar 81, the latter having at one end thereof a laterally off-set portion 83 which is secured to an end portion of the thermal flexible bar 79. The bimetal bar and the rigid bar therefore extend normally substantially parallel with each other and are spaced apart a relatively small distance. The connected ends of the bars 79 and 81 are pivotally mounted as on a fixed pivot pin 85 and a short coil spring 87 has one end there-

of connected with the rigid bar 81 and its other end interfitting with a wall of a small casing or box 89 within which the parts of the thermal timer are positioned.

The timer structure includes further a bar 91 which has one end thereof pivotally supported as by a stud or pin 93 in a bracket 94 permitting relatively limited vertical turning movement of the bar 91 as will be hereinafter set forth. The bar 91 is provided with two spaced projections 95 and 97 thereon which projections are spaced apart by a shouldered recess 99 shown more particularly in Figs. 1, 6, 7 and 8 of the drawings.

The bar 91 has mounted thereon a detent-holding and releasing plate 101 which is longitudinally movable on and relatively to the bar 91, being secured thereagainst by a plurality of pins 103 fixed in bar 91 and movable in elongated slots 105 in member 101. A short coil spring 107 biases member 101 toward the pivotal support 93 of member 91. It may be here pointed out that detent 69 is provided with a projection 109 which is adapted to engage against an end portion 111 of member 101, the upper surface of portion 111 extending angularly as is shown in the drawings for a purpose which will hereinafter appear. Member 101 is further provided at its other end with a lateral downwardly extending projection 113 which also has an angularly extending lower surface as will be noted by reference to Figs. 1, 6, 7 and 8 of the drawings.

The bimetal bar 79 has mounted thereon an auxiliary electric heating element 115 which is suitably insulated from the bimetal bar and which is connected in series circuit relation relatively to the main toast-heating elements hereinbefore described. I further provide a pair of fixed contact members 117 which contact members are connected to the ends of the auxiliary resistor 115 and which may be engaged by a contact bridging member 119 under certain operating conditions to be hereinafter described. The contact bridging member 119 is insulatedly mounted on and carried by a flange portion 120 on the pivotally mounted bar 91. A rod 121 extends vertically through the top portion of bottom plate 25 and has mounted thereon fixedly relatively thereto, a collar 123. The lower end of rod 121 is fixed in a laterally extending flange 124 on the movable end of bar 91. A biasing spring 125 has one end thereof engaging a washer 127 surrounding rod 121 and resting upon the top surface of member 25 while its upper end engages another washer 129 also loosely mounted on and surrounding the rod 121, the washer 129 being caused normally to engage fixed collar 123 whereby contact bridging member 119 is biased normally upwardly and out of engagement with the contact members 117. The upper end of rod 121 has mounted thereon loosely a collar 131 which is adapted to be engaged by a projection 133 constituting a part of carriage 43 and extending laterally therefrom. The portion 133 may have an opening therein through which the rod 121 extends. A second lateral projection 135 constitutes a part of the lower end of carriage 43 and has a recess therein large enough to permit collar 123 to pass therethrough so that projection 135 will engage washer 125 when the carriage is moved downwardly to remove the normal bias of coil spring 125. A second biasing coil spring 137 extends between the fixed collar 123 and the movable collar 131 so that when projection 133 is moved downwardly with the carriage, spring 137 will be compressed by downward movement of

projection 133 and of collar 131 to cause a downward bias of the contact bridging member 119.

At the start of a toasting operation the bimetal bar will be in the position shown more particularly in Fig. 1 of the drawings, from which it will be noted that biasing spring 87 causes engagement of one face of the bimetal bar 79 with projection 95 of bar 91. Since the auxiliary heater 115 is energized simultaneously with the energization of the toast heating elements, heat will be generated therein and the design and construction of bimetal bar 79 is such that heat received by it from the auxiliary heater 115 will cause it to bow to a position shown for instance in Figs. 6 and 7 of the drawings. Since the free end of bimetal bar 79 is held against projection 95 by biasing spring 87, it is obvious that the bimetal bar on heating will not move bodily but that it will only bow at its intermediate portion substantially as shown in Figs. 6 and 7 of the drawings. This results in a turning movement of rigid bar 81 in a counter-clockwise direction as seen in Figs. 6, 7 and 8 of the drawings, and the normal position of projection 113 is such that rigid bar 81 is positioned therebelow or in other words, projection 113 on member 101 is out of the path of movement of rigid bar 81 during heating up of the bimetal bar 79. This is because the bimetal bar 79 is supported on a fixed pivot pin 85 extending, in the toaster shown in the drawings, in a vertical direction so that its outer end will support the bar 91 in its initial substantially horizontal position, the upper edge of bimetal bar 79 engaging the lower edge of bar 91 closely adjacent to projection 85.

I provide a manually adjustable stop means for the moving end of rigid bar 81, comprising a shaft 141 having thereon a cam member 143, the shaft 141 extending outwardly through a bearing portion 145 of the skeleton frame 23 and having mounted thereon an adjusting arm 147 to permit of an operator turning the shaft and the cam 143 thereon in selected direction. Cam 143 is positioned between flange portions 149 secured to or constituting a part of a bar 151 which bar may have elongated slots 153 therein into which fixed pins 155 extend, these pins being secured to one of the portions of casing 89. It is therefore obvious that turning movement of arm 147 will result in turning movement of the cam 143 and movement of the bar 151 which is provided with a stop portion 157 at that end thereof adjacent to rigid bar 81.

Referring now to Fig. 6 of the drawings, the parts of the timer and detent-releasing structure comprising particularly the bimetal bar 79 and the rigid bar 81 are shown in the positions they will occupy when the bimetal bar has been heated and therefore bowed to an extent sufficient to cause engagement of the rigid bar 81 with the stop portion 157. It is to be understood, as already pointed out, that actually the structure comprising the bimetal bar and the rigid bar are in a plane at right angles to the bars 91 and 101. At this time further turning movement of rigid bar 81 away from the bimetal bar 79 will stop and the bimetal bar 79 will now be forced to move slightly in a clockwise direction out of engagement with the edge portion of the bar 91 adjacent to projection 95 thereon and the free end of the bimetal bar 79 can and will then enter the recess 99 whereby downward movement of the free end of bar 91 will result with attendant downward movement of contact bridging member

119 into engagement with the contact members 117 whereby deenergization of the auxiliary heating element 115 is effected. Another result of this turning movement of bar 81 on its pivot 5 83 is that projection 113 is now in the path of the return movement of rigid bar 81 which return movement is caused by the cooling bimetal bar 79 reducing its bowing, with resultant clockwise movement of the rigid bar 81.

It is therefore evident that coincident with cooling of the bimetal bar 79, one end of which is pivotally mounted on the pivot pin 85, and the other end of which is pivotally held by interfitting in the recess 99 of the bar 91, the rigid bar 15 81 will move in a clockwise direction and, as shown particularly in Fig. 8 of the drawings, the movable end of bar 81 will engage projection 113 when bimetal bar 79 has cooled to a predetermined temperature. Slight further cooling of the bimetal bar 79 causes additional turning movement of rigid bar 81 with resultant movement of member 101 until it and particularly its end portion 101 has been moved out of holding engagement with portion 109 of the detent 89. The upward pull on carriage 43 and particularly on arm 65, caused by the biasing spring 55, will therefore result in a turning movement of detent 69 in a clockwise direction with resultant release of portion 67 therefrom and spring 55 will therefore cause upward movement of the carriage 43 and of the bread carriers connected therewith.

It will be further evident that since compression of the spring 137 will be removed by upward movement of projection 133, the downward bias caused thereby will be removed and the bias effected by spring 125 will again be effective to cause upward movement of washer 129 against member 123 secured to rod 121 which will result in upward movement of rod 121, of contact bridging member 119 and also of the free end of bar 91 whereby all of the parts of the timer and detent-releasing structure will be returned to their normal initial or inoperative positions substantially as shown in Fig. 1 of the drawings so that the toaster is ready for the next succeeding toasting operation.

The structure including more particularly the bimetal bar 79 and the rigid bar 81 may be described as of relatively narrow U-shape and it may be further pointed out that both ends of the bimetal bar are substantially fixedly pivotally supported, at one end by the pivot pin 85, and at the other end by engagement with an edge portion of bar 91 and side engagement with projection 95 of bar 91.

As is already well known in the art, in the use of a single thermally actuatable element to constitute the motive power for a timer and for effecting release of a latch, an auxiliary switch must be operated when the thermal element reaches a maximum desired and predetermined temperature to stop heating of the thermal element and to then cause it to cool. One of the simplest forms of thermally actuatable element has been found by me to be a bimetal bar. When the bimetal bar has then been cooled to a predetermined lower temperature, it must cause, through suitable means, the release or tripping of a switch controlling the toast-heating elements or the release or tripping of the bread carriers which were moved into toasting position or it must cause both such actions simultaneously. It is further necessary that these parts must be reset for the next toasting operation, this,

of course, including movement of the toast-heating control switch parts to positions effecting de-energization of the toast-heating elements during the time intervals between toasting operations.

The hereinbefore described thermal timer and detent release means is effective to deenergize the auxiliary heating element associated with the bimetal bar at variable temperatures depending upon the position of the stop projection 157 engaged by the rigid bar 81 while the temperature at which termination of a toasting operation is effected is constant as to the cooling bimetal bar 79.

The structure comprising the bimetal bar and the rigid bar provides a relatively light-weight yet easily movable and relatively strong structure which is pivotally supported at the connected ends of the two bars so that there is relatively little or no wear of this pivotal support even after relatively long operation of a toaster of this kind. Since the auxiliary electric heater 115 does not move through any appreciable distance, it is a relatively simple problem to provide it with flexible leads connected either directly to the contact members 117 or to bars 159 and 161 suitably insulated supported in auxiliary casing 88 as by a plate 163 of electric insulating material.

The hereinbefore described device embodying my invention and providing a thermal timing and detent-releasing means requires a minimum number of parts which can be supported in a relatively simple means for the desired movements incident to operation thereof and I have found that a device of this kind can be easily and quickly assembled in a toaster and it is possible to easily and quickly vary the duration of a toasting operation to thereby provide different degrees of toasting of slices of bread, as may be desired by an operator.

While I have illustrated and described a single embodiment of my invention, it is obvious that further changes and modifications may be made therein and I therefore desire that all such modifications as clearly come within the scope of the appended claims shall be considered to be covered thereby.

I claim as my invention:

1. A thermal timer and detent-releasing structure for an automatic electric toaster comprising a toast heating element, a bread carrier movable into toasting and non-toasting positions relatively to the toast heating element and normally yieldingly biased into non-toasting position, means for moving the carrier into toasting position and a detent for holding the carrier in toasting position, said timer and detent-releasing structure including a bimetal bar, a rigid bar adjacent one side thereof, means securing one end of the rigid bar to one end of the bimetal bar and means pivotally supporting said secured ends, a spring biasing said bars in a given direction about said pivotal support, means including a stop lug engageable by the other end of the bimetal bar to prevent bodily turning movement of the bimetal bar in said given direction on its pivotal support, an auxiliary electric heater for causing heating of the bimetal bar and bowing thereof to allow said spring to cause turning movement of the rigid bar in said given direction, stop means engageable by said rigid bar when the bimetal bar has been heated to a predetermined temperature effective to cause limited bodily turning movement of the bimetal bar

in the opposite direction, latch means engageable by said other end of said bimetal bar to prevent return thereof in said given direction, means associated with said latch means to cause deenergization of the auxiliary heater upon engagement of said bimetal bar with said latch means, cooling of the bimetal bar and decrease of its bowing causing return turning movement of the rigid bar in said opposite direction, and detent-release means actuatable by the returning rigid bar when the bimetal bar has cooled to a predetermined lower temperature.

2. A device as set forth in claim 1 and including manually operable means to vary the position of the stop means and thereby vary the bimetal temperature at which the rigid bar engages the stop means.

3. A thermal timer and detent-releasing structure for an automatic toaster comprising a toast heating element, a bread carrier movable into toasting and non-toasting positions relatively to the toast heating element and normally yieldingly biased into non-toasting position, means for moving the carrier into toasting position and a detent for holding the carrier in toasting position, said timer and detent-releasing structure including a bimetal bar, a fixed pivotal support for one end of said bimetal bar, a stop lug for the other end of said bimetal bar, a rigid bar adjacent one side of the bimetal bar having one of its ends secured to the pivoted end of said bimetal bar, a spring yieldingly biasing said bars in a given direction on said pivotal support to hold the other end of said bimetal bar against said stop lug, means for flexing and unflexing said bimetal bar and for causing turning movement of the rigid bar first in said given direction and then in the opposite direction by heating and cooling the bimetal bar and a detent holding means adapted to be actuated by the rigid bar when the same is turning in said opposite direction.

4. A thermal timer and detent-releasing structure for an automatic electric toaster comprising a toast heating element, a bread carrier movable into toasting and non-toasting positions relatively to the toast heating element and normally yieldingly biased into non-toasting position, means for moving the carrier into toasting position and a detent for holding the carrier in toasting position, said timer and detent-releasing structure including a bimetal bar, a rigid bar normally extending substantially parallel to the bimetal bar, one end of said rigid bar being secured to one end of said bimetal bar, a fixed pivotal support for said secured ends, spring means biasing said bars in a given direction, means holding the other end of the bimetal bar in substantially fixed position against said bias, said bimetal bar being adapted to be heated and then cooled to cause flexing and unflexing of the bimetal bar and turning movement of the rigid bar first in said given direction and then in the reverse direction and detent holding means initially out of the path of movement of the rigid bar when said rigid bar is turning in said given direction and moved into said path of movement when the bimetal bar has reached a predetermined high temperature and engaged by said rigid bar in its movement in the reverse direction when the bimetal bar has cooled to a predetermined lower temperature to cause release of the detent.

5. A thermal timer and detent-releasing structure for an automatic electric toaster comprising

a toast heating element, a control switch therefor yieldingly biased to open position, means for closing said switch and a detent for holding said switch in closed position, said timer and detent-releasing structure including a bimetal bar, a rigid bar normally extending substantially parallel to the bimetal bar, one end of said rigid bar being secured to one end of said bimetal bar, a fixed pivotal support for said secured ends, a spring means biasing said bars in a given direction, means holding the other end of the bimetal bar in substantially fixed position against said bias, means for heating said bimetal bar, means to stop heating of the bimetal bar when it has been heated to a given temperature, the bimetal bar then cooling, said bimetal bar flexing in a given direction when heated to cause turning movement of said rigid bar in said given direction and flexing in an opposite direction when cooling to cause turning movement of said rigid bar in an opposite direction and detent-holding means initially out of the path of turning movement of said rigid bar and moved into said path of movement when the bimetal bar has been heated to said given temperature and engaged by said rigid bar when the bimetal bar has been cooled to a predetermined lower temperature to cause release of the detent.

6. A thermal timer and detent-releasing structure for an automatic electric toaster comprising a toast heating element, a bread carrier movable into toasting and non-toasting positions relatively to the toast heating element and normally yieldingly biased into non-toasting position, means for moving said carrier into toasting position and a detent for holding the carrier in toasting position, said timer and detent-releasing structure including a bimetal bar, a fixed pivotal support for one end of said bimetal bar, a stop lug for the other end of said bimetal bar, spring means for yieldingly biasing said bimetal bar against said stop lug, said bimetal bar being adapted to be heated and then cooled to cause flexing and unflexing thereof, means fixedly secured to the pivotally secured end of said bimetal bar and turned by the bimetal bar when heating in one direction and then turned by the bimetal bar when cooling in the opposite direction and detent releasing means engageable by the means fixedly secured to the pivotally mounted end of the bimetal bar when the bimetal bar has cooled to a given temperature.

7. A thermal timer and detent-releasing structure for an automatic electric toaster comprising

- a toast heating element, a control switch for said toast heating element normally yieldingly biased to open position, means to cause closing of said switch to initiate a toasting operation and a detent for holding said switch closed, said timer and detent-releasing structure including a bimetal bar, a rigid bar normally extending substantially parallel to the bimetal bar, one end of said rigid bar being secured to one end of said bimetal bar, a fixed pivotal support for said secured ends, spring means biasing said bars in a given direction, means holding the other end of the bimetal bar in substantially fixed position against said bias, means to heat said bimetal bar, means to stop heating thereof when it has reached a given high temperature, the bimetal bar flexing while being heated and causing said rigid bar to turn in said given direction and then cooling when heating thereof has stopped and causing said rigid bar to turn in the opposite direction and detent holding means initially out of the path of movement of the rigid bar when it is turning in said given direction and moved into said path of movement when the bimetal bar has reached said given high temperature and engaged by said rigid bar in its movement in the reverse direction when the bimetal bar has cooled to a given lower temperature to cause release of the detent.
8. A thermal timer and toasting-operation-terminating structure for an automatic electric toaster comprising toast heating elements and means for initiating a toasting operation, said thermal timer and toasting operation terminating structure including a bimetal bar, a pivotal support for one end of said bimetal bar, a rigid bar normally extending substantially parallel with said bimetal bar, one end of said rigid bar being secured to the pivotally supported end of the bimetal bar, spring means biasing said bars in a given direction, means holding the other end of said bimetal bar in substantially fixed position against said bias, means to heat said bimetal bar, means actuatable by the bimetal bar to stop heating thereof when it has reached a given temperature, the bimetal bar flexing while being heated to cause turning movement of the rigid bar in said given direction and then cooling when heating thereof has stopped and causing said rigid bar to turn in the opposite direction and terminate a toasting operation when the bimetal bar has reached a given lower temperature.

JOHN R. GOMERSALL.
